MACHINE FOR APPLYING LABELS OR TAGS TO ARTICLES FOR THE LAUNDRY, &c.

1,085,117.

Specification of Letters Patent.

Patented Jan. 27, 1914.

Application filed November 14, 1908. Serial No. 462,710.

To all whom it may concern:

Be it known that I, JOSEPH FRENCH, a citizen of the United States, residing at Woonsocket, in the county of Providence, 5 State of Rhode Island, have invented a certain new and useful Improvement in Machines for Applying Labels or Tags to Articles for the Laundry, &c., of which the following is a specification, reference being had 10 therein to the accompanying drawings.

The invention consists in mechanism for automatically attaching short lengths of tape or other suitable material by means of stitches to various articles, to serve as labels 15 or tags or for other purposes. The said mechanism is adapted, for instance, for attaching such labels or tags to articles of apparel or other personal use, household linen, etc., about to undergo the operations 20 of a laundry or of a cleaning establishment, or analogous treatment, and for attaching them to articles of apparel, or other articles of woven and knit goods, or of leather, or to parts of such articles, in connection with 25 manufacturing processes.

In carrying my invention into effect I employ, in combination, devices for presenting the label or tag in proper position with relation to the article to which it is to be 30 attached, and holding it in the correct relation therewith while the two are being fed in unison to the stitch-forming devices, stitch-forming devices serving to secure the label or tag to the said article by means of 35 stitches, and devices for feeding the article and label or tag to the stitch-forming devices for the stitching operation. In forming successive labels or tags from a continuous strip, I also employ devices for severing 40 from a supply of strip-material a section suitable in size for a label or tag, and an automatic device for feeding the continuous strip from the supply.

A feature of the invention is the combination with the foregoing devices of driving devices adapted to be thrown into action at the will of the operator to actuate the working parts to attach a label or tag, and arranged to arrest the action of such parts 50 automatically as soon as the predetermined number of attaching stitches shall have been made.

The invention in its more complete form is shown embodied in an automatic machine 55 in the drawings, in which latter,

Figure 1 is a front elevation of the said

machine, it being on a larger scale than Figs. 2, 3 and 4. Fig. 1^a is a detail. Fig. 2, Sheet 2, is an elevation thereof from the right hand side in Fig. 1. Fig. 3, Sheet 3, is an elevation thereof from the left-hand side in Fig. 1. Fig. 4, Sheet 4, is a plan view thereof. Figs. 5 and 6, Sheet 1, respectively are views in section on lines 5, 5, and 6, 6, respectively, of Figs. 2, 3 and 4. Fig. 7, Sheet 2, is a view of the presser in horizontal section in the plane of line 7, 7, Fig. 2, on a somewhat enlarged scale. Fig. 8, Sheet 3, is a view in section on line 8, 8, of Figs. 2, 3, and 4, showing the clutch and stop-devices. Fig. 9, Sheet 5, is a face view of a portion of an article having a label attached thereto, showing the result of the action of the machine illustrated in the drawings. Fig. 10, same sheet, is a back view thereof. Fig. 11, same sheet, is a sectional detail of the said article and tag on an enlarged scale.

Having reference to the drawings,—at 1 is shown a convenient base or bed, at 2 the work-support of a sewing machine, at 3 the upright portion or post rising from the said work-support, at 4 the overhanging arm of the sewing machine, and at 5 the head of the said machine. The stitch-forming mechanism of the machine may vary in character 80 in practice. It is in this instance of an ordinary two-thread lock-stitch type, and may be of any preferred construction, the needle being shown at 6, Figs. 2 and 3, and the needle-bar at 7. Work-feeding devices of suitable character are employed, the toothed portion of a feed-dog of usual kind being shown at 8, Figs. 1, 2 and 3. By means of such work-feeding devices the garment or other article to which a label or tag is being attached, and the label or tag, are advanced together in the machine as the successive stitches are formed. The supply or upper or needle-thread is furnished by a spool at 10, Figs. 2 and 4, guides for such thread on its way to the needle being shown at 11, 11, and a needle-thread take-up device being in part shown at 12.

At 13 is a presser-foot or presser, and at 14 is the presser-bar. The said parts 13 and 14, as usual in the case of the presser-foot and presser-bar of a sewing machine, are movable toward and from the work-support in a vertical direction, and are furnished with a convenient spring, as presently 105 described, operating with a tendency to bear them toward the work-support so as to keep 110

the presser down upon an article resting on the said support. In addition, for the purposes of the invention, they are made movable back and forth parallel with the line of feed. These different movements are provided for in the present embodiment of the invention by fixing the presser-bar at its upper end upon a short horizontal shaft 15, Figs. 2, 3 and 4, extending parallel with the 5 arm 4 and above the latter and fitted to bearings which are provided in the free ends of arms 16, 16, fixed upon a rocking sleeve 17, which last is fitted to bearings in the arms or brackets 18, 18, rising from post 3 and 10 head 5. The presser and presser-bar are kept normally in their starting position at the right in Fig. 1, with the presser-bar in contact with a stop-pin 21 projecting from the head 5 of the machine, by means of a 15 spiral spring 19 surrounding the shaft 15 and having one end thereof engaged with the standard 20 rising from such shaft, as shown in Fig. 2. This spring acts with a tendency to turn the shaft 15 in its bearings 20 in the arms 16, 16, until the presser-bar engages with the said stop-pin 21, and to keep the presser-bar in such engagement. The spring above referred to, that is employed for the purpose of moving the presser-bar 25 and presser down toward the work-support 2 and the work resting thereon, and maintaining the downward pressure of the presser, is in this instance a contracting spiral spring 26. It has the lower end 30 thereof engaged with the arm 4 of the machine, and the upper end thereof engaged with an adjustable screw 27 carried by one of the arms 16. Lifting movement is automatically communicated to the presser-bar 35 and presser at the predetermined times in the working of the machine by movement of partial rotation imparted to the sleeve 17 through devices comprising an arm 22, Figs. 1, 2 and 3, fixed upon the rear end of the 40 sleeve, and a cam-projection 23, Figs. 1 and 5, upon a gear-wheel 24. Such projection extends inward from the rim 24^a of the said gear-wheel toward the center of the latter, and it acts against a pin or roll at 25 carried by the said arm 22. Normally, the 45 machine stands at rest, with the said cam-projection in engagement with the said pin or roll and with the sleeve 17 and its arms 16, 16, in a position which holds the presser 50 uplifted above the work-support so as to facilitate the insertion of an article, as *b*, Figs. 2 and 3, and a label, as at *a'*, under the presser and between it and the work-support. When the machine is started, the 55 first portion of the turning movement of the gear-wheel 24 carries the cam-projection 23 out of engagement with the pin or roll 25, whereupon the spring 26 acts to turn the sleeve and its arms in the direction to move 60 the presser toward the work-support, caus-

ing the presser to clamp the label and article together and against the work-support 2. The machine being in motion, stitches are made by the action of the stitch-making devices, thereby uniting label *a* to article *b*, 70 and by the movements of the feed-dog 8 the said article and the label are fed in unison from right to left in Fig. 1 past the needle. As they are thus fed the frictional engagement between the under surface of the 75 presser and the surfaces of the label and article *b* causes the presser and presser-bar to accompany the label and article against the opposition of the spring 19, the presser-bar swinging about the axis of shaft 15 as 80 a center.

The presser is constructed to guide the label *a'* into position to be stitched, and to remain in engagement with the same, holding it in place upon the article *b*, until it 85 has been attached to the latter. The devices of the illustrated machine are, in conformity with one feature of the invention, constructed and arranged to attach the label to the article by a line of stitches crossing 90 the width of the label, as indicated in Figs. 9, 10, and 11. Accordingly, the presser operates to guide the label *a'* so that as the latter passes into position to be stitched to the article it extends at right angles to the 95 line of feed. To this end, the presser is formed at its front side with an open notch, 36, Fig. 7, of a width properly proportioned to the label *a'*, the opposite sides of the said notch being continued above the presser by 100 side-walls 35, 35, upon the presser-bar constituting edge-guides for the label. It is because the label is engaged in this manner with the presser, and remains thus engaged during the operation of stitching across its 105 end, that the presser is mounted to accompany the work as the latter is fed along in the machine during the stitching operation.

The label *a'* may be of any material suitable for the purposes of a label or tag and 110 adapted to be stitched to the article *b*. Usually, I employ woven tape. For greater convenience, I prefer to form successive labels or tags from a continuous strip *a* of material suitable for employment for the 115 purposes of labels or tags, for instance woven tape as just specified, which is conducted by suitable guides to a point adjacent the stitch-making point. This strip is shown drawn from a roll 28, mounted 120 upon a pin 29 carried by the standard or upright 20, the said roll having in connection therewith, for the purpose of preventing too free a delivery of the tape, a drag device comprising a frictional shoe 30, resting upon 125 the top of the roll, such shoe being connected with a slide 31 movable up and down upon the standard or upright, and weighted as at 32 to cause it to press upon the periphery of the wound mass of tape. The strip 130

as it is extended from the roll to the presser passes through guides at 33, 34, and then between the side-walls 35, 35, of the presser-bar, it being held in flattened condition by means of the cross-pin 35^a which extends from one of the said side-walls to the other. The tape passes behind the said cross-pin and is thereby confined in proper position to be engaged by the strip-feeder.

As has been stated, the machine normally stands at rest, with the cam-projection 23 in engagement with the pin or roll 25 of arm 22, and the presser elevated as in the drawings. The leading end of strip *a* having been caused to extend a short distance below the presser, the machine is in readiness for attaching a label to the desired article. In beginning operations, the said article *b* is entered from the front in Fig. 1, that is, from the left-hand side in Fig. 2, in beneath the presser. As it is carried under the latter, it pushes the hanging end of the strip *a* in with it so that such end extends rearward beyond the position of the needle, as at *a'* in Figs. 2 and 3, but usually somewhat to the right of such position. When, now, the machine is set in motion, the cam-projection 23 is carried past the pin or roll 25, thus permitting spring 26 to rock the sleeve 17 and its arms 16, 16, and move the presser down upon the article *b* and the label *a'* which overlies the same. In its lowered position the presser holds the material of article *b* in engagement with the teeth of the feed-dog 8, so that the latter in its movement shall operate to feed the said article and label from right to left together to the needle. The revolution of gear-wheel 24 is so timed that as soon as the label *a'* in being fed along with the article *b* has been carried transversely to the left to the required extent with relation to the needle the cam-projection 23 arrives again in engagement with the pin or roll 25 and operates through the intermediate connections to transmit movement to lift the presser once more. As this occurs the machine comes to rest as hereinafter explained, leaving the presser in its uplifted position.

A characteristic feature in connection with the presser is the fact, above referred to, that while it is yieldingly pressed down upon the end of the strip, *i. e.* the label *a'*, and the portion of article *b* underlying the same, it is carried forward in the direction of the feed, that is, from right to left in Fig. 1, by frictional engagement with the said strip and article as these latter are advanced, *i. e.*, fed, by the action of the feed-dog. This forward movement of the presser in the direction of the feed is essential, since the side-walls 35, 35, of the presser-bar and the corresponding side-walls of the notch in the presser constitute edge-guides for the strip, and it is necessary that the guiding-means

for the strip should advance in unison with the article *b* as the latter is fed, so that the label may be carried crosswise past the needle.

For the purpose of severing from the continuous strip *a* the portion thereof, *i. e.* label, which has been stitched to the article *b*, I provide a suitable cutter-device. Herein, the latter comprises a fixed blade 37, Fig. 1, a movable blade 38, and actuating means for the said movable blade. The said fixed blade is provided upon the presser-bar. The movable blade is fixed upon the lower end of a substantially upright shaft 39 that is mounted in bearings which are provided upon the presser-bar at 40, 40. To insure efficient cutting action, the bearings for the said upright shaft are so disposed as to cause the axis of the shaft to occupy a position that is slightly inclined out of parallelism with the longitudinal axis of the presser-bar. The axis of the shaft leans away at its upper end from that of the presser-bar, in the direction of the feed, as illustrated in Fig. 1. In addition, an expanding spiral spring 41 surrounds the shaft 39 between the lower bearing 40 and an adjustable collar 42, which latter is clamped by its securing screw upon the shaft 39 in such position as to maintain a proper degree of compression of the spring. The spring acts with a tendency to lift the shaft vertically endwise, thereby holding the upper side of the movable blade 38 in contact with the under side of the fixed blade 37. The result of this action of the spring, and the effect of the inclination of the cutter-shaft 39, are to cause the edge of the movable blade to bear closely and firmly alongside the edge of the fixed blade, thereby insuring perfect cutting action. For the purpose of operating the movable blade to cut the strip *a*, the cutter-shaft 39 has fixed thereon an arm 43 which is connected by a universal joint at 44 to one end of a connecting rod 45, the other end of which is connected by a universal joint 46 with the upwardly extending arm of a bell-crank 48, Figs. 1 and 3, which is pivoted upon the stud 49 projecting from the post 3. The horizontal arm of the said bell-crank has connected therewith one end of a contracting spiral spring 50, the other end of which is connected with the work-support 2, this spring acting to hold the movable cutter-blade in its open position and the said horizontal arm of the bell-crank in contact with a fixed stop at 51. For the purpose of operating the cutter-device at the proper time in the working of the machine, a pin 52, Figs. 2, 4, and 5, is provided upon the rim of the gear 24. As this pin comes around in the rotation of the said gear, it engages with the horizontal arm of the bell-crank, and, pressing the same upward, transmits movement through the described connec-

tions to the cutter-shaft 39 and the movable cutter 38 carried thereby. As soon as the pin has passed beyond the horizontal arm of the bell-crank and released the same, the 5 spring 50 operates to restore the parts to their normal position and opens the movable cutter-blade. The reason for employing universal joints in the connections at 44 and 49 is the fact that while the stitching of the 10 strip α' to the article b is in progress the presser-bar carrying the cutter-bar moves forward in unison with the strip and article, as above described, whereas the bell-crank always remains and swings in the same 15 plane. After the cutting operation has been performed the continuous portion of the strip α is fed downward automatically to a sufficient extent to cause its leading end to project below the presser, as before, a distance sufficient to enable the same to be 20 pushed in under the uplifted presser and across the line of stitching in beginning the operations of attaching a fresh label or tag to a succeeding article. This moving or 25 feeding of the continuous strip down is effected by means of the strip-feeding dog 54, Fig. 1, which is constituted by a bent spring strip working at its acting extremity between the side walls 35, 35, of the presser-bar, and toothed at such extremity to engage 30 with the strip. This strip-feeding dog is attached to the guide 34, which latter in turn is formed upon a slide 55 movable upon the presser-bar in the direction of the length 35 of the latter. Thereby the said strip-feeding dog is attached to the said slide. For the purpose of operating the slide and strip-feeding dog, the said slide has connected therewith pivotally at 56 the lower end of a 40 connecting-rod or link 57, the upper end of which is pivotally connected with an arm 58 fixed upon a rock-shaft 59 extending through the sleeve 17, and having fixed upon its rear end an arm 60 to which is connected 45 pivotally the upper extremity of a link 61 having its lower extremity joined pivotally with a lever 62, shown best in Fig. 6, Sheet 1, carrying a pin or roller 63 working in a groove 64 in the back side of the gear-wheel 50 24, the said lever being pivoted at 65 to a stand or bracket 66 rising from the base or bed 1.

The result of the action of the machine as herein described is illustrated in Figs. 9, 10, 55 and 11, in which the label α' is shown attached to the article b by two threads α^2 and α^3 , which are formed into stitches passing through the said label and article and thus uniting the former to the latter. The 60 number of stitches may vary, as deemed advisable. It will be observed that the thread α^2 is formed into loops α^4 passing through the article and label from one side of these latter to the other thereof, and the thread 65 α^3 is extended through the said loops at the

said other side, thus locking the loops so as to prevent their withdrawal. These stitches may be produced in practice by adjusting the tensions of the respective threads of the two-thread lock-stitch sewing mechanism so that the thread α^3 shall be under relatively heavy tension, and the thread α^2 under relatively slight tension. This adjustment of the tensions permits the loops α^4 of the thread α^2 to be extended through the article and label by the taut thread α^3 , the said thread α^3 remaining in straight condition at its side of the article and label. As thus combined, the threads hold the label to the article. One or more stitches are made in the article at each side of the label, as shown, so that strain upon the label may not start the stitches and disconnect the label. Loose ends of the thread are left projecting at both ends of the line of stitches as shown, partly for the same reason, but chiefly to serve as pull-ends which may be grasped for the purpose of pulling out the threads to enable the label to be detached. In practice I usually employ a thread α^3 which, by reason of the nature of its material, or the treatment to which it has been subjected, or its greater size, is less liable to yield and bend than the thread α^2 . This favors the straight position of the thread α^3 in the stitches, and enables this result to be attained with less difference in the tension of the two threads. I have shown the thread α^3 a little coarser than thread α^2 . A coarse thread is easier to grasp and pull upon than a fine one. For convenience in severing the two threads when the required line of stitches has been made, I provide a thread-cutting device upon the front end of the work-support, such device comprising the fixed blade 67 and the slotted guide 68 coöperating with the cutting edge thereof. At the conclusion of the operation of forming the line of stitches, the presser having been raised, the article is pulled out from beneath the same, drawing out both the upper thread and the under thread from their sources of supply. The operator then causes the threads to make contact with the cutting edge of the blade 67, thereby severing them.

At 69 is shown a band-pulley for the reception of the driving-band (not shown) to be employed in transmitting power for the purpose of actuating the machine. Intermediate the said pulley 69 and the gear-wheel 24 and main shaft 70, Figs. 2 and 3, of the sewing mechanism, from which the stitching devices and work-feeding devices are operated, I employ motion-transmitting devices including a clutch and having combined therewith means for operating the said clutch to throw the same into action at the will of the operator. The parts just referred to are so constructed and combined that each time the clutch is thrown into action it remains in

action, causing motion to be transmitted to the gear-wheel 24 and shaft 70, until the sewing mechanism has been operated to produce the required number of stitches and the 5 other working parts have been actuated to perform the operations which are incident to attaching a label, severing the same from the strip α , and feeding the said strip forward in readiness for the attachment of the 10 next label, and then the said clutch automatically ceases to act and the stitching devices and other working parts come to rest.

A convenient arrangement of motion-transmitting train and clutch-device is 15 shown in the drawings, in which latter the shaft 71 of pulley 69 is furnished with a spur-pinion 72 meshing with the loose spur-gear 73 upon the shaft 74 of gear 24. The gear 24 serves by engagement with the spur-pinion 24^b fixed upon the main shaft 70 of the sewing machine to operate the latter. Spur-gear 73 is shown in dotted lines in Fig. 8. The clutch-device, see more particularly Fig. 8, comprises a toothed wheel 75 20 which is fixed to the spur-gear 73 and like the latter is loose upon the shaft 74, an arm 76 mounted upon the shaft 74 and made fast thereto by the clamping-screw 77, a clutch-dog 78 pivoted to the arm 76, and a contracting 25 spiral spring 79 having one end thereof engaged with the working end of the clutch-dog 78, and the other end thereof engaged with a pin upon the arm 76. The spring 79 acts with a tendency to draw the working 30 end of the clutch-dog 78 into engagement with the teeth of the toothed wheel 75, and keep it in such engagement. Normally the clutch-dog is held disengaged from the toothed wheel 75 by means of a clutch-con- 35 trolling lever 80, which is pivoted at 81 upon a fixed stand 82, and acted upon by an expanding spiral spring 83 which tends to hold the working end of the said lever 80 in position to act against the tail of the 40 clutch-dog 78. Engagement of the lever with the tail of the clutch-dog holds the working end of the latter out of engagement with the teeth of the toothed wheel 75, and while this is the case the wheels 75 and 73 remain un- 45 connected with shaft 74, and when rotated by turning movement of the pulley 69 and its spur-pinion 72 simply turn loosely upon the shaft 74. When, however, the lever 80 is moved by the operator so as to carry its 50 working end away from the tail of the clutch-dog 78 and permit the spring 79 to move the working end of the clutch-dog into engagement with the teeth of the wheel 75, the wheels 75 and 73 become clutched to the 55 shaft 74, thereby causing rotary movement to be transmitted to the wheel 24, with the result that the working parts of the machine are actuated. Having started the machine 60 into action in the manner just described, the operator permits lever 80 to resume its nor-

mal or tripping position, inasmuch as it is intended that at the conclusion of a rotation of the gear-wheel 24 the tail of the clutch-dog 78 shall encounter the working end of the said lever 80 so that the clutch-dog 78 70 shall thereby be disengaged from the teeth of toothed wheel 75, thus unclutching the wheels 75 and 73 from shaft 74 and causing the machine to come to rest. In order to prevent overrunning of the machine when thus unclutched, the arm 76 is furnished with a projecting portion 84, and the lever 80 is furnished with a projection 85 which passes into the path of the projection 84, and by engagement therewith positively 80 stops the rotation of the said arm and of the shaft 74 and gear-wheel 24, etc. To prevent recoil of the parts the lever 80 is furnished with a shoulder 86, which, by engagement with the tail of the dog, serves to prevent 85 recoil of arm 76 when the projection at 84 brings up solidly against the projection 85.

It will be perceived that the gear 24 through its actuation of the spur-pinion 24^b serves to operate the stitch-forming devices, 90 and by means of its cams and the pin 52 serves to actuate the presser-raising and lowering devices, the strip-feeding device, and the cutter. Hence, when the said gear is in motion the machine is operative; when 95 the said gear stands at rest the machine is inoperative.

In order to gain sufficient time for commencing and terminating the operations in connection with the attachment of a label to an article I may, as shown in the drawings, utilize intermittent gearing for the actuation of the stitch-forming devices. Thus, as shown best in Fig. 6, a portion of the circumference of the gear-wheel 24 is without 100 teeth, in order that while the toothless portion is moving past the spur-pinion 24^b the latter may remain motionless. Thereby, the said pinion and the stitch-forming devices are permitted to remain at rest for a short 105 time at the beginning of the rotation of the gear-wheel 24, and they also are permitted to come to rest a little before the completion of the rotation of the gear-wheel 24 and to remain at rest while such rotation terminates. To hold the pinion 24^b locked so as to prevent the same from turning, and the stitch-forming devices from changing position, while the blank portion of the gear-wheel 24 is presented to the said pinion, I 110 form the pinion with a flange 24^c which is concave at one side as indicated in Fig. 5, and upon the gear 24 I provide a segmental convex locking surface 24^d for engagement with the concavity of the flange 24^c. While 115 the convexity occupies the concavity the pinion 24^b is held from turning, but as the convexity passes out of the concavity in the turning movement of the spur-gear 24, the first tooth on the latter succeeding the blank 120 125 130

space comes into engagement with one of the teeth of the spur-pinion 24^b, thereby setting the latter and the stitch-forming devices in motion.

5. While I have illustrated the invention as embodied in a machine constructed to produce a single line or series of stitches, I do not limit myself with respect to the latter.

What is claimed as the invention is:—

10. 1. In combination, stitching devices, a work-feeding device, a presser movable in the direction of the feed and adapted to accompany the work as the latter is fed by the said device, and a guide adapted to guide the leading end of a label-strip into position

15. to be extended across the line of stitching at an angle to such line, said guide moving in unison with the presser.

20. 2. In combination, stitching devices, a work-feeding device, a presser movable in the direction of the feed and adapted to accompany the work as the latter is fed by the said device, a guide adapted to guide the leading end of a label-strip into position to be extended across the line of stitching at an angle to such line, said guide moving in unison with the presser, and means for stopping the stitching on the completion of a predetermined number of stitches.

25. 3. In combination, stitching devices, the overhanging machine-head, a presser mounted on the said head and movable in the direction of the feed and adapted to accompany the work as the latter is fed, a feed-dog engaging with the work to feed the latter, and a guide adapted to guide the leading end of a label-strip into position to be extended across the line of stitching at an angle to such line, said guide moving in

30. unison with the presser.

40. 4. In combination, stitching devices, a work-feeding device, a presser movable in the direction of the feed and adapted to accompany the work as the latter is fed by the said device, a guide adapted to guide the leading end of a label-strip into position to be extended across the line of stitching at an angle to such line, said guide moving in unison with the presser, and means to sever a label from the strip.

45. 5. In combination, stitching devices, a work-feeding device, a presser movable in the direction of the feed and adapted to accompany the work as the latter is fed by the said device, a guide adapted to guide the leading end of a label-strip into position to be extended across the line of stitching at an angle to such line, said guide moving in unison with the presser, means for stopping the stitching on the completion of a predetermined number of stitches, and means for severing a label from the strip.

50. 6. In combination, stitching devices, a work-feeding device, a presser movable in the direction of the feed and adapted to ac-

company the work as the latter is fed by the said device, a guide moving in unison with the presser adapted to present the leading end of a label-strip in position to be extended across the line of stitching, means for severing a label from the strip, and means for feeding or advancing the strip to enable its end to be presented for the next label.

7. In combination, stitching devices, a work-feeding device, a presser movable in the direction of the feed and adapted to accompany the work as the latter is fed by the said device, a guide moving in unison with the presser, means for feeding a continuous label-strip to said guide for each successive label and into position to be extended across the line of stitching, means for severing a label from the strip of which it forms a part, and means for stopping the stitching operation when a predetermined number of stitches has been made across the label.

8. In combination, stitching devices, work-feeding devices, a work presser constructed with means to guide a label into a position in advance of the needle, means to feed a strip of label-material to present a label-length thereof adjacent to the stitching devices, a label-cutting device, presser-lifting devices, and operating means constructed to operate the parts for the production of the required number of stitches uniting the label to the garment or other article, and arrest the working thereof with the work-presser in an elevated position and the leading portion of a fresh label in readiness for presentation to the stitching devices and attachment to a subsequent garment or other article.

9. In combination, stitching devices, work-feeding devices, a work-presser constructed with means to guide a label transversely with relation to the line of feed and movable with the label in the direction of such line, presser-lifting devices, and operating means constructed to operate the parts for the production of the required number of stitches uniting the label to the garment or other article, and arrest the working thereof with the work-presser in an elevated position.

10. In combination, stitching devices, work-feeding devices, a work-presser constructed with means to guide a label transversely with relation to the line of feed and movable with the label in the direction of such line, means to feed a strip of label-material, a label-cutting device, presser-lifting devices, and operating means constructed to operate the parts for the production of the required number of stitches uniting the label to the garment or other article, and arrest the working thereof with the work-presser in an elevated position.

11. In combination, stitching devices, work-feeding devices, a presser constructed

to guide a label, presser-lifting devices, means to feed a label-strip, a cutter to sever a label from such strip, and operating connections for the working parts, including a driver gear-wheel, as 24, having a blank space and a locking flange, and a driven gear-wheel, as 24^b, having a locking convexity which coacts with the said flange in

holding such pinion and the stitching and work-feeding devices from motion. 10

In testimony whereof I affix my signature in presence of two witnesses.

JOSEPH FRENCH.
